US00D946380S

(12) **United States Design Patent** (10) Patent No.: **US D946,380 S**
 Raymond et al. (45) Date of Patent: **** Mar. 22, 2022**

(54) **RECTANGULAR FLOOR GROMMET**(71) Applicant: **Raymond & Lae Engineering, Inc.**,
 Fort Collins, CO (US)(72) Inventors: **Donald M. Raymond**, Fort Collins, CO
 (US); **Jeremy D. Swanner**, Fort
 Collins, CO (US); **Timothy L.**
Hirschenhofer, Fort Collins, CO (US);
James M. Schneider, Fort Collins, CO
 (US)(73) Assignee: **RAYMOND & LAE ENGINEERING,
 INC.**, Fort Collins, CO (US)(***) Term: **15 Years**(21) Appl. No.: **29/718,184**(22) Filed: **Dec. 20, 2019**(51) LOC (13) Cl. **09-06**

(52) U.S. Cl.

Primary Examiner — Cynthia R Underwood

(74) Attorney, Agent, or Firm — Cochran Freund &
 Young LLC; William W. Cochran(57) **CLAIM**The ornamental design for a rectangular floor grommet, as
 shown and described.**DESCRIPTION**FIG. 1 is a top isometric view of a rectangular floor grommet
 showing my design.FIG. 2 is a bottom isometric view of the rectangular floor
 grommet.

FIG. 3 is a top view of the rectangular floor grommet.

FIG. 4 is a bottom view of the rectangular floor grommet.

FIG. 5 is a front view of the rectangular floor grommet.

FIG. 6 is a back view of the rectangular floor grommet.

FIG. 7 is a left side view of the rectangular floor grommet;
 and,

FIG. 8 is a right side view of the rectangular floor grommet.

1 Claim, 8 Drawing Sheets(56)
